UNITED STATES PATENT OFFICE.

FREDERIC G. NICOLAUS, OF CLEVELAND, OHIO, ASSIGNOR TO AMERICAN STOVE COMPANY, OF ST. LOUIS, MISSOURI, A CORPORATION OF NEW JERSEY.

STOVE-DOOR HINGE.

1,159,254.

Specification of Letters Patent.

Patented Nov. 2, 1915.

Application filed July 13, 1915. Serial No. 39,632.

To all whom it may concern:

Be it known that I, FREDERIC G. NICOLAUS, a citizen of the United States, residing at Cleveland, in the county of Cuyahoga and State of Ohio, have invented certain new and useful Improvements in Stove-Door Hinges, of which the following is a specification, reference being had therein to the accompanying drawing.

10 My invention relates to improvements in stove door hinges.

The object of my invention is to provide a hinge of this character which is readily secured to the door-frame by means of a 15 single bolt and which obviates the necessity of drilling holes in the door-frame for securing the hinge thereto.

Another object of my invention is to provide a stove door hinge of this character 20 in which the wearing parts can be readily removed and replaced and at the same time providing a simple, cheap and effective hinge having certain details of structure and combination of parts hereinafter more fully 25 set forth.

In the accompanying drawing—Figure 1 is a perspective view of a portion of a stove showing my improved hinge applied. Fig. 2 is a vertical sectional view taken on the 30 line 2—2 of Fig. 1, showing the door in its operative position. Fig. 3 is an enlarged perspective view of the door, stove-frame and the several parts forming my hinge in their disassembled relation.

35 Referring now to the drawings, 1 represents the frame of my improved stove which is preferably made of angle iron, and one leg 2 of the angle iron is preferably cut away, as indicated at 3, and having communicating with the upper end of the cut-away portion 3 a cut-away portion 4, extending vertically, as fully shown in Fig. 3 of the drawing. This cut-away portion of the leg 2 of the angle iron is all that is necessary to form means for locking the hinge bearing to the stove-frame. The cut-away portion 3 forms a space in which projects the enlarged portion 5, carrying the pintle 6 of the hinge. This cut-away portion 3 40 allows the door to be swung around and is so arranged that it can be moved beyond a line at right angles to the stove frame. The portion 5, as heretofore described, is secured to the stove-door 7, which is made of any desired form, as this forms no part of my in-

vention. The stove-frame is cut-away as indicated at 8, to allow for the head of the pintle bearing, which I will now proceed to describe.

The pintle bearing is formed of a circular 60 head portion 9 having its lower edge cut away to allow the enlarged portion 5 of the pintle carrying member to pass the same so as to allow the door to tightly close. This enlarged head is provided with an inwardly 65 extending body-portion 11, which is of a width equal to that of the cut-away portion 4 in the angle iron 1. The upper edge of the portion 11 is curved to fit the upper curved cut-away portion 4. Extending inwardly from the center of the enlarged portion 11, is a screw-threaded extension 12, which will be later described. The portion 11 is provided with a vertically disposed opening 13, extending therethrough and into 70 which the pintle 6 carried by the enlarged portion 5 of the stove door passes and is free to oscillate therein.

In assembling the several parts of the hinge, the pintle bearing is passed over the 80 pintle 6, the pintle entering the vertical opening 13 and the portion 11, together with the enlarged portion 5 of the stove door, are brought into the position of the cut-away portions 3 and 4, respectively, of the stove-frame. The head 9 fits against the outer face of the leg 2 of the angle iron and limits its inward movement. Loosely fitting over the screw threaded portion 12 of the pintle bearing is a saucer-shaped member 14, which 85 has its lower edge cut away, as indicated at 15 to allow for the outward movement of the enlarged portion 5 of the stove door. This saucer-shaped member is provided with an opening 16, through which the threaded 90 portion 12 carried by the pintle bearing extends. Screwed upon the screw-threaded portion 12, of the pintle carrying member is a nut 17, which bears against the outer face of the saucer-shaped member 14, and forces the same inwardly against the inner face of the leg 2 of the angle iron, forming the 95 stove-frame and securely locks the pintle carrying member to the said stove-frame. This saucer shaped member allows the nut 100 to be securely locked thereon and removed without interfering with the enlarged portion 5 carrying the pintle 6.

The angle iron 1 of the stove-frame is provided with a second pintle carrying member, 110

as shown in Fig. 1, which is arranged exactly like the one heretofore described, except that the slots or cut-away portions 3 and 4 are oppositely arranged. That is the 5 cut away portion 4 extends downwardly instead of upwardly in respect to the cut-away portion 3. The lower pintle-carrying member 5 has a pintle 6 extending from its lower face instead of its upward face, and from 10 this it will be seen that the door is rigidly supported by the two pintle carrying members which are secured to the single nut and the door-frame does not need any boring for the openings for securing the pintle-carrying member thereto.

15 While I have shown this specific form of pintle-carrying member, it will be seen that the same could be varied without departing from my invention.

20 Having thus described my invention, what I claim and desire to secure by Letters Patent is—

1. The combination with a stationary member having a cut-away portion in one 25 edge, of a movable member having a pintle carrying member wholly within said cut-away portion, and means secured within the cut-away portion and extending transversely of the stationary member and forming a 30 bearing for said pintle.

2. The combination with a member having a cut-away portion on one edge, of a movable member having a pintle carrying member within the said cut-away portion, 35 and a locking bolt extending transverse of the stationary member within the cut-away portion and forming a bearing for said pintle.

3. The combination with a member having cut-away portions in one edge, of movable members having pintle carrying members within the cut-away portions of the stationary member, and locking bolts extending transverse of the stationary member 45 and forming bearings for said pintles.

4. The combination with a stationary member having a cut-away portion in its edge, of a movable member having a pintle carrying member within said cut-away portion, and a locking bolt secured within the cut-away portion transverse of the stationary member, and forming a bearing for said 50 pintle.

5. The combination with a stationary member having cut-away portions, of a movable member having pintle-carrying members entering said cut-away portions, locking bolts having heads at one end and a screw-threaded portion at the opposite end, 55 and a pintle bearing intermediate the head and screw-threaded portion.

6. The combination with a stationary member, of a movable member having a pintle and a locking bolt having a head at 60 one end and a screw-threaded portion at

the opposite end, and an intermediate portion forming a bearing for said pintle.

7. The combination with a stationary member having cut-away portions in one edge, of a movable member having pintle 70 carrying members within said cut-away portions, locking bolts extending through the cut-away portions, transverse of the stationary member, and having openings forming bearings for said pintles.

8. The combination with a stationary member having cut-away portions, of a movable member having pintle carrying members entering the cut-away portions, said stationary member having cut-away portions 80 communicating with the before-mentioned cut-away portions, and locking bolts secured within the last mentioned cut-away portion and forming bearings for said pintles.

9. The combination with a member having cut-away portions, of a door having pintle-carrying members entering said cut-away portions, and locking bolts having heads entering the cut-away portions of the member, and locking bolts having heads formed on one end, a threaded portion at the opposite end and an intermediate enlarged portion entering the cut-away portion in the member and having an opening there-through forming bearings for said pintles.

10. The combination with a member having horizontally arranged cut-away portions, of a door having pintle-carrying members entering said horizontally arranged cut-away portions, a vertically disposed cut-away portion communicating with the horizontally arranged portion and locking bolts having heads at one end and a threaded portion at the opposite end, and an enlarged 100 intermediate portion fitting within the vertical cut-away portion of the member and having openings therein forming bearings for said pintles, a cup-shaped member fitting over the screw-threaded end of the locking bolts and nuts on the screw threaded end of the bolt on the outside of the cup-shaped member.

11. The combination with a stationary member having cut-away portions in its edge, of a movable member having pintle carrying members entering the cut-away portion, said stationary member having cut-away portions communicating with the before-mentioned cut-away portions, and locking bolts passing transversely through the last-mentioned cut-away portion of the stationary member, and adapted to be clamped thereto and forming bearings for said pintle.

12. The combination with a stationary member having cut away portions, of a door having pintle carrying members entering the said cut-away portions, and locking bolts entering the cut-away portions of the member, said locking bolts having heads on one 120 130

side of the member and nuts on the opposite side of the member, and clamping them to the said member and said bolts having means intermediate the heads and the nuts 5 for forming bearings for said pintles.

13. The combination with a stationary member having a cut-away portion, of a movable member having a pintle carrying member entering the said cut-away portion, 10 locking bolts extending transversely through

the stationary member adjacent the cut-away portion and having a head at one end and a nut at the opposite end and intermediate bearings for said pintles.

In testimony whereof I hereunto affix my 15 signature in the presence of two witnesses.

FREDERIC G. NICOLAUS.
